UNITED STATES PATENT OFFICE.

JOSEPH E. LOWDEN, OF CINCINNATI, OHIO, ASSIGNOR TO THE GEORGE E. LEE COMPANY, A CORPORATION OF OHIO.

REGULATOR FOR MELTING-POTS.

1,156,239.

Specification of Letters Patent.

Patented Oct. 12, 1915.

Application filed August 6, 1913. Serial No. 783,367.

To all whom it may concern:

Be it known that I, JOSEPH E. LOWDEN, a citizen of the United States, residing at Cincinnati, in the county of Hamilton and State 5 of Ohio, have invented certain new and useful Improvements in Regulators for Melting-Pots, of which the following is a specification.

This invention relates to melting pots, and 10 is particularly but not exclusively adapted for use in connection with the metal pots of linotype or other type casting machines.

The invention comprises a regulator for controlling the flow of gas used to heat the 15 metal for supplying the metal to the feeding pot as fast as it is needed.

The regulator is shown applied in connection with an auxiliary melting pot or cup which supplies molten metal to the feeding 20 pot from which the metal is taken in the operation of the machine, the regulator being so constructed and arranged that the flow of gas to the burner under the melting pot or cup is controlled by the height of metal in 25 the main or feeding pot, whereby the metal is maintained at a uniform height, and the apparatus will be free from the many objections incident to metal too hot or too cold, as well as effecting a saving of gas and having 30 other advantages which will be apparent to those skilled in the art.

One embodiment of the invention is illustrated in the accompanying drawings in which—

35 Figure 1 is a side elevation partly in section of the device. Fig. 2 is a detail in top plan view of the gas connections to the regulator. Fig. 3 is a section through the head of tube 17.

40 Referring specifically to the drawings, 6 indicates the main or feeding pot in which the molten metal is contained. This is supported on the frame of the machine in any suitable way, as by a hanger 7.

45 8 indicates a melting cup or pot which receives the ingot 9, and from which cup the molten metal drops through an opening 10 into the main pot 6, as fast as the metal is melted. A standpipe 11 surrounds the cup 50 8 and acts as a guide and confines the heat. A burner 12 is located under the melting cup 8. These parts are supported by a bracket

13 clamped to a part of the machine indicated at 14.

15 indicates the gas supply pipe which 55 leads to a pipe 16 depending in a tube 17 which hangs in the main pot 6, being supported by a hanger 18 attached to a part of the frame. The lower end of the tube 17 projects below the lower end of the inner 60 tube 16. From the head of the tube 17 a pipe 19 connects to the gas burner, and another pipe 20 extends from the head of said tube to a pilot light at the burner, said pipe 20 having a small passage communicating 65 with the pipe 15 in the head of the regulator, so that there is always a flow to the pilot light.

The lower open end of the tube 17 is always sealed by the metal in the pot 6, and 70 the lower open end of the supply pipe 16 is opened or closed automatically by the fall and rise of the metal in said pot. When the level of the metal is below the lower end of the pipe 16 it is opened and gas flows therefrom into the pipe 17 and thence to the main 75 burner which is lighted by the pilot and melts the metal in the cup 8 and the molten metal flows into the main pot until the level is raised sufficiently to close the mouth of 80 the pipe 16. This shuts off the gas and stops the melting action until the metal in the pot again falls below and opens the mouth of the tube 16, when the action is repeated.

85 It will be seen that the action of the burner and the melting of the metal thereby in the cup or auxiliary pot is automatically controlled by the rise and fall of metal in the main pot. This simple device therefore 90 serves its purpose under all conditions and automatically controls the supply of metal, and the device has the further advantage that it can be applied to existing machines, and is certain and effective in its operation. 95

What I claim as new is:

1. The combination of a main pot, a melting pot discharging into the same, a burner for heating the latter, and a fuel supply conduit to the burner, said conduit extending 100 into the main pot and having a supply opening which is opened and closed by the metal in said main pot, as it falls and rises.

2. A fuel regulator for metal pots, com-

prising, in combination with the pot, a burner for heating metal supplied to said pot, and means controlled directly by the height of metal in said pot for governing the fuel supply to said burner, including a conduit depending into the pot in position to be opened and closed by the metal therein, as it falls and rises.

3. The combination with a metal pot, and 10 a burner for heating metal supplied thereto, of a fuel supply conduit leading to said burner and having a part which dips into said pot and is provided with a supply opening controlled by the height of metal in said 15 pot.

4. The combination with a metal pot, and 20 a burner for heating metal supplied thereto, of outer and inner fuel supply pipes depending into the pot, one of said pipes communicating with the burner, and the other with the fuel supply, the inner pipe having an 25 opening communicating with the outer pipe and located above the lower end of the latter and adapted to be closed and opened by the rise and fall of the metal in the pot.

5. The combination with a metal pot, and 30 a burner for heating metal supplied thereto, of outer and inner fuel supply pipes depending into the pot, one of said pipes communicating with the burner and the other with the fuel supply, the inner pipe having an 35 opening communicating with the outer pipe and located above the lower end of the latter and adapted to be closed and opened by the rise and fall of the metal in the pot, and a pilot light adjacent to the burner.

6. The combination with a pot, and a 40 burner for heating material supplied thereto, of a fuel supply conduit to said burner, having two parts depending into the pot, with a communicating opening between said 45 parts located in position to be closed and opened by the rise and fall of material in the pot.

45 7. The combination with a pot, and a burner for heating material supplied thereto, of an outer pipe connected to said burner and depending at its open lower end into said pot, in position to be sealed by the 50 molten material therein, and an inner pipe connected to the fuel supply and provided with an opening located above the lower end of said outer pipe, in position to be closed and opened by the rise and fall of said material in said outer pipe.

8. The combination with a pot, and a 60 burner for heating material supplied thereto, of a fuel supply conduit to said burner provided with a fuel passage exposed to the material in said pot and directly controlled by the height of said material.

9. In a metal feeding apparatus for 65 linotype machines or the like, in combination with a pot and a separate melting device ar-

ranged to feed molten metal to the pot, a heater arranged in proximity to the melting device, a supply conduit for the fuel leading to the heater, and a fuel controller in the fuel supply conduit comprising a chamber provided with a fuel inlet and a fuel outlet 70 and having an opening therein covered by and admitting molten metal from the pot to the chamber to directly control communication between the inlet and outlet of the chamber.

75 10. In a metal feeding apparatus for linotype machines or the like, in combination with a pot and a separate melting device arranged to feed molten metal to the pot, a heater arranged in proximity to the melting 80 device, a supply conduit for the fuel leading to the heater, and a fuel controller in the fuel supply conduit comprising a chamber provided with a fuel inlet and a fuel outlet and having an opening therein cov- 85 ered by and permitting ingress and egress of the molten metal in the pot, so that the molten metal will stop the feed of fuel through the chamber when the molten metal rises in the chamber sufficiently to cut off 90 communication between the inlet and outlet of the chamber.

95 11. In a metal feeding apparatus for linotype machines or the like, in combination with a pot and a separate melting device ar- 100 ranged to feed molten metal to the pot, a heater arranged in proximity to the melting device, a fuel supply conduit leading to the heater, and a fuel controller in the fuel supply conduit comprising an outer tube having an open lower end covered by the molten metal in the pot, and an inner tube within the outer tube and having an open lower end in proximity to the upper surface of the molten metal in the pot, the outer tube being provided with a fuel inlet and a fuel outlet, one of which includes the lower end of the inner tube, so that the lower end of the inner tube is adapted to be covered or uncovered by the molten metal in the pot to 110 thereby control the supply of fuel to the heater.

115 12. The combination with a receptacle adapted to hold melted material, of an auxiliary receptacle or melting pot adapted to contain said material in solid form, a device for melting the material in said pot, a fuel feed pipe having an open end extending adjacent the surface of the melted material within said first mentioned reservoir, a chambered member surrounding said feed pipe, and extending into the said melted material, and a fuel ejection pipe communicating with the chambered member and also communicating with the heating device.

120 125 13. The combination with a receptacle adapted to hold melted material, of a crucible adapted to contain said material in a

solid form, a burner for melting the material in said crucible, a hollow body having an open end, which end is submerged beneath the melted material within the receptacle,

5 a fuel conducting means extending into said hollow body adjacent the surface of the liquid material, a fuel outlet means, means for introducing fuel to said fuel conducting means, and means for conducting

the fuel from the fuel outlet means to the burner.

In testimony whereof, I affix my signature in presence of two witnesses.

JOSEPH E. LOWDEN.
